UNITED STATES PATENT OFFICE.

THOMAS MAYES, OF ALBANY, NEW YORK; DAVID MUHLFELDER ADMINISTRATOR OF SAID MAYES, DECEASED.

FOLDING SUPPORT FOR HEAD-RESTS AND THE LIKE.

SPECIFICATION forming part of Letters Patent No. 480,822, dated August 16, 1892.

(Application filed January 21, 1891. Serial No. 378,508. (No model.)

To all whom it may concern:

Be it known that I, THOMAS MAYES, of Albany, in the county of Albany and State of New York, have invented a new and Improved 5 Folding Support for Head-Rests and the Like, of which the following is a full, clear, and exact description.

The object of the invention is to provide a support for head-rests and the like which may 10 be folded into small compass when not required for use and which may be readily erected to adapt it for use on a car-seat for supporting a head-rest, mosquito-canopy, or a lamp-bracket, all as hereinafter described 15 and claimed.

Reference is to be had to the accompanying drawings, forming a part of this specification, in which similar letters and figures of reference indicate corresponding parts in all the 20 views.

Figure 1 is a perspective view showing the support adjusted in position on a car-seat. Fig. 2 is a side elevation of the support, Fig. 25 3 a rear elevation, and Figs. 4 and 5 perspective views of different forms of head-rests.

The improved support is formed of two members A B, united by a hinge connection C to enable them to be folded together when not required for use or to be brought, respectively, to the horizontal and vertical positions, as shown. To the back of the vertical member B a rack B' is secured for engaging a pawl or similar catch d, carried by the head-rest D, said head-rest having a vertical opening d' for receiving the vertical member B and permitting the head-rest D to slide thereon. The horizontal member A is provided with a cross-bar A' for steadyng the support when erected on a car or other seat 10. Adjacent to the hinge 40 C each member A B is provided, respectively, with a block a b, which blocks are tapered outwardly for entrance between the upholstery of the car-seat at the juncture of the seat portion and back.

45 The top of the vertical member B is formed with a stud b' for receiving a lamp-bracket, as 15, or for the convenient attachment of a strap where it is desirable to strap the support to any convenient part of the car-seat.

50 The head-rest may be of the form shown in

Fig. 4 or that shown in Fig. 5. In the former the back D' of the head-rest, having the opening d' before mentioned, has secured to it two arms d² d², which are received in oppositely-located diagonal sockets formed in the back 55 D', the outer ends of the arms d² d² being oppositely curved to form a somewhat semicircular rest for a person's head, the head-rest being suitably cushioned or upholstered in practice. In the form shown in Fig. 5 a board or plate d³ 60 is secured to the face of the back D', and arms d⁴ d⁴ are secured to the said board or plate and suitably upholstered.

If desired, a skeleton frame E, as shown in Fig. 1, may be secured to the head-rest for 65 supporting a mosquito-canopy. An auxiliary seat F may be secured to the horizontal member A, if desired.

By means of the above-described portable support the comfort of travelers may be 70 materially increased, and the support may be conveniently carried by individuals to be erected whenever desired.

Having thus described my invention, what I claim as new, and desire to secure by Letters 75 Patent, is—

1. The combination, with the bar B to rest against the back of a car-seat and having a vertical rack B' on its rear face and the lower horizontal member adapted to rest on a car-seat under the occupant and hinged at its rear edge to the lower end of the rear bar B to fold against the front face thereof, of the head-rest D, having a vertical opening through 80 which bar B and its rack passes, and a pawl d on the rear of the head-rest, engaging the said rack, substantially as set forth.

2. The combination, with the bar B to rest against the back of a car-seat and having a vertical rack on its rear face, the lower horizontal member A to rest on a car-seat under the occupant and hinged at its rear edge to the lower end of the bar B to fold against the front face thereof, and the blocks a b on the backs of member A and bar B at the hinged 90 edges thereof to pass behind the upholstery on the car-seat and under the upholstery on the seat-back, respectively, of the head-rest provided with a vertical opening through 95 which passes the bar B and its rack and pro- 100

vided with a pawl to engage the rack, substantially as set forth.

3. The combination, with the bar B to rest against a car-seat back and provided with a rack on its rear side and a reduced upper end or bracket-receiving projection b' , the lower hinged member A, hinged to bar B to fold against the front face thereof, and the blocks b a on the adjacent ends of the bar B and

member A to enter the space between the car-seat and its back, of the head-rest D, having a vertical opening d' for the bar B and its rack, and a pawl d to engage the rack.

THOMAS MAYES.
